UNITED STATES PATENT OFFICE

153,190

DESIGN FOR AN AUTOMOBILE DOOR SUN SHADE

Orville W. Thraillkill, Wellington, Kans., assignor
to Albert R. Greer, Wellington, Kans.

Application October 28, 1946, Serial No. 134,323

Term of patent 7 years

(Cl. D14—6)

To all whom it may concern:

Be it known that I, Orville W. Thraillkill, a citizen of the United States, residing at Wellington, in the county of Sumner and State of Kansas, have invented a new, original, and ornamental Design for an Automobile Door Sun Shade, of which the following is a specification, reference being had to the accompanying drawings, forming part thereof.

Figure 1 is a view in side elevation of an automobile door sun shade, showing my new design, the dotted line showing of a portion of an automobile body being for illustrative purposes only.

Figure 2 is a view looking at the front end of the sun shade.

Figure 3 is a view in top plan of the same.

Figure 4 is a view looking at the inner side of the shade.

Figure 5 is a transverse section taken on the line 5—5 of Figure 3.

Figure 6 is a transverse section taken on the line 6—6 of Figure 3.

Figure 7 is a transverse section taken on the line 7—7 of Figure 3.

Figure 8 is a transverse section taken on the line 8—8 of Figure 3.

I claim:

The ornamental design for an automobile door sun shade, as shown and described.

ORVILLE WM. THRAILKILL.
